UNITED STATES PATENT OFFICE

2,401,486

BEVELING MACHINE

Norman E. Jones, Toledo, Ohio, assignor to The
Toledo Plate & Window Glass Company, Toledo,
Ohio, a corporation of Ohio

Application December 6, 1943, Serial No. 513,079

1 Claim. (Cl. 51—132)

1

This invention relates to edge beveling machines, and particularly to those for beveling glass plates of circular form.

An object of the invention is the provision of a machine of this character wherein the work being ground has rotating coaction with the side of a rotary grinding wheel, as distinguished from its periphery, so as to (a) present a broad surface for the grinding operation, (b) enable the contact of the work with the wheel to be shifted over the grinding surface to effect substantially uniform wear, and (c) cause the grinding action to serve as the dressing means for the wheel, thus prolonging the effective life of the wheel and enhancing the practicability and commercial value of the machine.

Another important object of the invention, resulting from grinding contact of the work to be beveled with the side of the grinding wheel, is that it enables the radial width of a bevel and the speed of grinding to be varied by shifting the point of contact of the work with the wheel transverse to a radial line of the wheel which intersects the axis of rotation of the work.

A further object of the invention is the provision in a grinding machine of the class described and wherein a marginal side edge portion of a rotary work piece has grinding coaction with a side of a rotary grinding wheel, of means for adjusting the face plane of one of said rotating members to that of the other to effect an angular engagement of the members to suit the desired inclination of the bevel being ground.

A further object of the invention is the provision in a grinding machine of the class described, and wherein a marginal side edge portion of a rotary work plate has grinding coaction with a side of a rotary grinding wheel, of means for relatively positioning the work plate and grinding wheel whereby they are disposed in diverging planes of rotation suitable for the angle of the bevel to the work plate edge with the wheel intersecting a registering radius of the wheel at an angle which is other than normal thereto.

Further objects and advantages of the invention will be apparent from the following detailed description, and from the accompanying drawings, in which—

Figure 1 is a plan view of the machine embodying one form of the invention and in which two work carrying units are shown, with the work pieces carried thereby of different sizes and in beveling engagement with different side portions of a single grinding wheel; Fig. 2 is a side elevation of the machine, one work carrying unit only

2

being shown; Fig. 3 is a vertical section on the line 3—3 in Fig. 1, with the stone contacting area of each work piece more or less diagrammatically shown; Fig. 4 is a similar view illustrating the relatively small point of beveling contact of the work piece with the stone when such point falls on a line which substantially intersects the axes of rotation of both work piece and stone; Fig. 5 is a fragmentary view of a grinding wheel and coacting work piece in the relative positions of engagement shown in Fig. 4 and with the work piece in initial sharp edge coaction with the wheel; Fig. 6 is an enlarged fragmentary view of Fig. 3 illustrating the line of contact of the work piece with the wheel with the bevel finished; and Fig. 7 is a fragmentary section on the line 7—7 in Fig. 6.

Referring to the form of the invention shown in Figs. 1 to 7 of the drawings, 1 designates a base frame or standard at the top of which, in suitable bearings 2, is mounted the shaft 3 carrying at one end the grinding wheel 4. This shaft, in the present instance, is horizontally disposed and has driven belt and pulley connection 5 with a motor 6 mounted in the base portion of the frame 1. The wheel 4 is clamped to a fixed collar 7 on the shaft 3 by a nut 8 at its outer side, thus permitting easy removal and replacement of the wheel. The working side of the wheel 4, the outer side in the present instance, is preferably but not necessarily formed on a bevel 4^a, or of conical form, so that the wheel gradually diminishes in thickness from an area near its center to its outer edge.

On a frame 10, at the grinding wheel side of the machine, are mounted, in the present instance, two work-piece carrying units A and B positioned for the respective work-pieces C and D carried thereby to have edge beveling engagement with the tapered side of the wheel 4 at opposite sides of its axis.

Each unit A, B, includes a base plate 12 that is clamped to the top of the frame 10 for various horizontal adjusting movements by bolts 13 extending through slots 14 in the base plate and crossing slots 15 in the frame top. A shaft 16 is mounted for rotary and axial movements in bearings 17 rising from the base plate 12 and is disposed for its axis to intersect the plane of rotation of the grinding wheel 4. This shaft is driven by a motor 18 through a suitable change speed connection comprising, in the present instance, a belt and variable V-pulley connection 19, between the motor shaft and a lower shaft (not shown), and a belt and pulley connection 20, be-

tween such lower shaft and the shaft 16. The motor is mounted on a bracket 21 projecting from and movable with the base plate 12.

The work C or D, as the case may be, may and usually does constitute a glass plate of circular form and is concentrically clamped to a work holding plate 22 on the shaft 16 by vacuum action in order to leave the edge of the plate free and prevent the necessity of providing holes in the plate for attaching a securing means thereto. The shaft has a longitudinal passageway 23 therethrough opening at one end at the work-piece clamping side of the plate 22 and at its other end to a vacuum source (not shown) through a flexible tube 24, thus enabling a vacuum to be created at the plate end of the shaft to hold a work plate thereto. The work plate has a sealing fit against the holding plate to prevent relief of the vacuum, as well understood in the art.

The work plate is positioned for its edge to lap a side of the grinding wheel 4, the tapered side in the present instance, and its axis of rotation is horizontally adjusted relative to that of the wheel, as may be desired, by a horizontal adjustment of the base plate 12 on the frame 10. In order to move the work plate into and out of engagement with the grinding wheel, the shaft 16 is axially shiftable in any suitable manner. This is accomplished, in the present instance, by shifting the shaft axially in its bearing and effecting such shifting by movements of a hand lever 26, one arm of which has forked connection with a collar 27 on the shaft.

In order to obtain the most efficient, speedy and economical beveling action it is desirable to so dispose the axis of rotation of the work plate with respect to that of the grinding wheel that the work plate edge engages a side face of the wheel at a point which is offset laterally from a line *a* (Figs. 3 and 4) which intersects the axes of the wheel and work plate, or substantially so, with the plane of rotation of one disposed in intersecting or tilted relation to that of the other, so that thelapping portions of said faces are spaced at said line. This relative positioning of the faces is accomplished, in the present instance, by tilting the shaft 16 in a vertical plane by raising the outer end of the base plate 12 of the work carrying unit by the manipulation of a screw 30 which threads up through the top of the frame 10, as shown in Fig. 2. The clamping bolts 13 must, of course, be first loosened.

If the area of contact of the wheel and work is substantially coincident with the line *a*, as shown at *b* (Fig. 4), the area of contact is small, the wearing or disintegrating action on the stone is severe and the grinding of the work bevel is comparatively slow due to the circular line of the work edge crossing the radial line *a* at an angle substantially normal thereto. With this relationship the sharp edge *c* (Fig. 5) of the work plate not only cuts into the stone surface, thus quickly grooving or rendering the stone surface irregular, but the length of contact of the work edge with the stone can never be greater than the width of the ground bevel. If, however, the work-piece and stone are relatively tilted so that the point or area of beveling contact is at one or the other side of the line *a*, the edge line *c* of the work, at its point of contact with the stone, is disposed obliquely to an intersecting radial line, such as *d*

(Fig. 3) of the stone, so that the area of beveling action, compared with that shown in Fig. 4, is not only prolonged circumferentially of the work, but also radially of the stone surface, as shown at *e* (Figs. 3, 6 and 7). This materially lessens the grooving of the stone face during the grinding action and speeds up the grinding operation. It is apparent that the more remote the point of grinding is from the line *a* the more nearly will the line of circumferential contact of the work edge with the stone register lengthwise with an intersecting radial line of the stone.

It will be noted that in the embodiment of the invention illustrated in Figs. 1 to 4, the axes of rotation of the work-piece and grinding wheel are relatively divergent in two planes, one plane, for the purpose of identification, being horizontal and common to both axes, and the other plane being vertical or in intersecting relation to the first plane. The divergence of the axes in the so-called horizontal or common plane, or toward each other, while preferable in practice, is not necessary, but the other relative positioning of the axes whereby the work-piece and wheel havelapping coaction in divergent relation at one side of a line intersecting the two axes is important in this embodiment of the invention and is the particular feature that produces the improved result desired.

If the machine is provided with two work carrying units, as illustrated, they should be positioned so that the work-pieces carried thereby may engage the same grinding wheel at opposite sides of its axis and preferably at points on the face of the wheel which are differently spaced from its axis, thus causing a more even wear of the wheel surface. In practice, the grinding wheel is driven at a high speed and the work-pieces are driven at relatively low speeds. It is found that a speed of approximately 225 R. P. M. of the wheel and 28 R. P. M. of the work-piece produces good results. This speed may, of course, be varied to suit the particular grinding conditions, and for this purpose either or both of the stone and work plate drives may include a variable drive feature.

I wish it understood that my invention is not limited to any specific construction, arrangement or form of the parts, as it is capable of numerous modifications and changes without departing from the spirit of the claim.

Having thus described my invention, what I claim as new, and desire to secure by United States Letters Patent, is:

In a plate edge beveling machine, two transversely spaced shafts, means for driving each of said shafts, a frusto-conical abrading wheel carried by one shaft and the other shaft having means adapted to carry a workpiece to rotate therewith with its face plane normal to its axis of rotation, means for supporting one of said shafts including a frame, a base plate on said frame, and bearing means on said base plate receiving said last mentioned one of said shafts, means for shifting said last mentioned one of said shafts axially of said bearing means, said means for driving said last mentioned one of said shafts comprising a motor mounted on said base plate, and adjustable means fixedly securing said base plate to said frame in position to maintain the axes of rotation of said shafts relatively divergent in both horizontal and vertical directions.

NORMAN B. JONES.

It is to be understood that the above described grinding machine is to be used for grinding stone and not for metal.
